UNITED STATES PATENT OFFICE.

IRA V. SPURLIN, OF HAMILTON, OHIO.

DUSTPAN FOR FLOOR-SURFACING MACHINES.

Application filed October 25, 1926. Serial No. 144,098.

This invention relates to new and useful improvements in dust pans for floor surfacing machines particularly adapted for use in conjunction with the "American Universal" floor surfacing machine, manufactured by The American Floor Surfacing Machine Company of Toledo, Ohio.

In the type of floor surfacing machine above identified, the same is equipped with a detachable edge sanding drum in order to permit the machine to surface the floor at the edges thereof, and said drum may be disposed at either end of the usual hollow shaft of the main drum. In this type of machine no provision is made for catching the dust and dirt created by the operation of the drum and it is therefore the primary object of the present invention to so construct a dust pan that will catch the dirt and dust created by the edge sanding drum regardless of the end of the main drum to which the same is attached.

A further and important object resides in the provision of a dust pan of this character that may be readily associated with the machine in lieu of the usual pan, and this without requiring any alterations of the existing stock parts of the machine.

A further and important object is to provide a dust pan that is equipped with a removable cover plate that may be disposed upon the pan for closing the entire area of the same with the exception of that portion thereof directly in back of the edge sanding drum in order that the entire force of the air suction will be in back of said edge sanding drum to effectively receive all of the dust and dirt created during the operation of said edge sanding drum.

A further and important object is to provide such a dust pan wherein the cover may be inserted within the end thereof dependent upon the end of the main drum with which said sanding drum is associated.

Other objects will become apparent as the nature of the invention is better understood, the same comprising the novel form, combination, and arrangement of parts herein-after more fully described, shown in the accompanying drawing and claimed.

In the drawings, wherein like reference characters indicate corresponding parts throughout the several views:

Figure 1 is a fragmentary side elevation of an "American Universal" floor surfacing

machine equipped with a dust pan constructed in accordance with the present invention.

Figure 2 is a fragmentary front elevation of the machine, the main sanding drum having been removed for disclosing my dust pan in front elevation, the removable cover plate being partly broken away so as to more clearly disclose the interior construction of the pan. 60

Figure 3 is a vertical section through the machine directly in back of the dust pan for disclosing the same in rear elevation. 65

Figure 4 is a detail vertical section taken substantially upon the line 4—4 of Figure 2 for more clearly disclosing the means whereby the cover plate of the pan may be detachably secured to said pan. 70

Figure 5 is a similar view taken substantially upon the line 5—5 of said Figure 2 for more clearly disclosing the method of attachment of the entire pan to the machine frame, and 75

Figure 6 is a perspective of the cover plate for the pan. 80

Now having particular reference to the drawings, 5 indicates generally a floor surfacing machine of the "American Universal" type equipped at its forward end with the usual main sanding drum 6 pivotally attached at its opposite end to the frame 7 in the form of a casting and upon the top side of which is disposed an electric motor 8 for operating the sanding drum, said frame being equipped at its opposite side 85 directly rearwardly of the main sanding drum with the usual truck wheels one only of which is disclosed and designated by the reference character 9. 90

My invention per se consists of a dust pan 10 in the form of a metallic casting, the same being of arcuate shape throughout its transverse area, the same as the type of pan now in use upon the machine. Leading from the center of said pan 10 is the usual rectangular dust inlet 11 that merges into an exhaust nozzle 12 that is in communication with the usual suction fan of the machine, not shown. In this connection, attention is invited to Figure 3 wherein it will be noted that this rectangular inlet 11 is of a length considerably less than the pan 10 and thus it is constructed to accommodate small floor surface engaging rollers to facilitate movement and to prevent the lower 100

portion of the pan from engaging obstructions or irregular floor surfaces.

The present pan 10 is considerably longer than the pan with which this type of sanding machine is now equipped in order that the same will project slightly beyond the ends of the main sanding roll 6.

Formed upon the rear surface of the pan 10 at the opposite ends of the inlet opening 11 are hollow boxings 13-13 formed with vertical slots 14-14 in registration with similar slots 15-15 in the main body of the pan 10 so as to facilitate the attachment of the pan to the frame casting 7 by machine screws 16-16. The rear surface of each boxing 13 is of plano-configuration so as to permit the pan to be secured in flush engagement with the forward end of the frame casting 7, the slots in the boxings and pan being respectively for the purpose of permitting the vertical raising and lowering of the pan to accommodate uneven floor surfaces and to permit a screw driver to be engaged with the screws during the attachment and removal of the pan with respect to the machine frame.

Pivoted between ears 17-17 upon the rear surface of the pan 10 directly outwardly of the machine frame 7 and adjacent one end thereof is a pivotal latch dog 18, the upper end of which is provided with an outwardly projected pin 19 movable through an opening 20 in said pan while arranged between the lower end of the latch dog and said pan is an expansible coil spring 21 for normally maintaining the pin 19 of the dog in full engagement to the opening 20 as clearly indicated in Figure 4.

Furthermore, the opposite longitudinal edges of the pan 10 are formed with angular undercut lips 22-22 for receiving the beveled longitudinal edges of a cover plate 23, which cover plate is also of arcuate formation throughout its transverse area as disclosed in Figures 4, 5 and 6. Upon the rear surface of this cover plate at opposite corners and adjacent opposite ends thereof are recesses 24-24, for receiving the pin 19 of the latch dog 18 regardless of into which end of the pan 10 said cover plate is inserted.

At the outer end of the cover plate 23 the same is formed with an arcuate shaped housing 25, the front and inner side wall of which is open as clearly indicated in Figure 6.

The opposite ends of the pan 10 are open, while the end of the cover plate 23 opposite from the end carrying the housing 25 is formed upon its rear surface with a rearwardly projecting wall 26, the edge of which is of curvilinear formation so as to engage the adjacent end of the dust pan 10 to afford an end wall for said dust pan.

Obviously when the previously mentioned

edge sanding drum (not shown) is associated with either end of the main sanding drum 6 the cover plate 23 is so disposed within the pan 10 that the housing 25 will be arranged directly in back of said end sanding drum to catch the dust and dirt created by the same. By reason of the cover plate 23 being disposed upon the open side of the pan 10, the entire air suction will be through the housing 25 so that all particles of dust and dirt will be sucked through said housing and subsequently into the pan 10 and then through the nozzle 12 into the usual dust bag.

From the foregoing description and drawings it will be evident that I have evolved and produced a novel product of manufacture in the form of an attachment to take the place of the customary dust collecting pan now in use on floor surfacing machines on the type hereinbefore referred to. I might state again, that in machines of this character, the manufacturers provide a supplementary sanding drum which is referred to in the trade as an edge standing drum. Incidentally, it is slightly larger in diameter than the main drum and when it is in place the main drum is raised off the surface of the floor. Also, the old pan is rigidly mounted on the body portion of the machine, is of generally arcuate formation, open on its front side to collect the dust, and has closed end walls. In the present arrangement, however, the pan 10 is open at its opposite ends and the longitudinal top and bottom edges are provided with the aforesaid angularly directed lips 22 for slidable reception of the removable cover plate 23. My dust pan is regarded as an improvement over the old pan in that it is adjustably mounted and can be raised up or down to obtain the desired spacing from the floor surface to overcome any possibility of dragging. It runs on small rollers and is thereby caused to move more smoothly. The cover plate 23 can be slid in from either end of the pan and when the edging sand drum is not in use, the cover plate and receptacle 25 carried thereby can be removed for convenient transportation. The receptacle 25 is of course arranged at the end of the main drum upon which the edging or supplemental drum is mounted. In this way the floor dust which is beat up by the small drum is collected in the receptacle 25 and swept into the pan 10 underneath of the cover 23 as is indicated in Figure 2. These and other advantages and features of the invention have doubtless been made apparent by the foregoing description and drawings, for which reason a more lengthy description is believed to be unnecessary.

Having thus described the invention, what I claim as new and desire to secure by Letters Patent is:-

1. In a dust pan for floor surfacing machines, a pan unit constructed for attachment to the machine frame rearwardly of the sanding drum, a cover plate for said pan, and a housing at one end of the plate open at its front and inner end, said housing extending beyond the end of said sanding drum and having communication with said dust pan in it when the cover plate is associated therewith.

2. In a dust pan for floor surfacing machines, a pan unit constructed for attachment to the machine frame rearwardly of the sanding drum, a cover plate for said pan, and a housing at one end of the plate open at its front and inner end, said housing extending beyond the end of said sanding drum and having communication with the dust pan when the cover plate is associated therewith, and means whereby the cover plate may be maintained in rigid association with said dust pan.

3. In a dust pan for floor surfacing machines, a pan unit constructed for attachment to the machine frame rearwardly of the sanding drum, a cover plate for said pan, and a housing at one end of the plate open at its front and inner end, said housing extending beyond the end of said sanding drum and having communication with the dust pan when the cover plate is associated therewith, means whereby the cover plate may be maintained in rigid association with said dust pan, said means being of such a construction as to permit the cover plate to be inserted through either end of the pan so as to dispose the housing at either end of said sanding drum.

4. In a dust pan for floor surfacing machines, a pan unit constructed for rigid attachment to the machine frame in back of the usual sanding drum, a cover plate for the pan, and an open front sided and inner ended housing at one end of the cover plate projecting beyond the end of the pan when the cover plate is applied thereto, said hous-

ing having communication with the interior of the pan for collecting dust created beyond either end of said sanding drum.

5. In a dust pan for floor surfacing machines, a pan unit constructed for rigid attachment to the machine frame in back of the usual sanding drum, a cover plate for the pan, and an open front sided and inner ended housing at one end of the cover plate projecting beyond the end of the pan when the cover plate is applied thereto, said housing having communication with the interior of the pan for collecting dust created beyond either end of said sanding drum, and means whereby the cover plate is detachably secured to the pan when associated therewith.

6. In a dust pan for floor surfacing machines, a pan unit constructed for rigid attachment to the machine frame in back of the usual sanding drum, a cover plate for the pan, and an open front sided and inner ended housing at one end of the cover plate projecting beyond the end of the pan when the cover plate is applied thereto, said housing having communication with the interior of the pan for collecting dust created beyond either end of said sanding drum, and means whereby the cover plate is detachably secured to the pan when associated therewith, said means being of such construction as to permit the cover plate to be inserted within the pan from either end thereof.

7. In a structure of the class described, a dust collecting and conveying device adapted to be mounted on a conventional type of floor surfacing machine employing a main drum and a detachable edging drum, said device comprising a main pan adapted to be adjustably mounted on the machine for co-operation with the main drum, and a convertible auxiliary dust collecting receptacle in communication with the main pan and detachably mounted on said main pan.

In testimony whereof I affix my signature.

IRVING SPURLIN.
